ATTORNEY.

UNITED STATES PATENT OFFICE.

JAMES R. SLOAN, OF ALTOONA, PENNSYLVANIA.

BATTERY VENT-PLUG.

1,010,695.

Specification of Letters Patent.

Patented Dec. 5, 1911.

Application filed June 9, 1911. Serial No. 632,108.

To all whom it may concern:

Be it known that I, JAMES R. SLOAN, a citizen of the United States, residing at Llyswen, Altoona, Blair county, Pennsylvania, have invented an Improved Battery Vent-Plug, of which the following is a specification.

My invention is an improved vent plug designed to permit the free escape of gas, to prevent the escape of solution and drain it back into the cell, to prevent the introduction of foreign matter, and to facilitate the inspection of the interior of the cell.

The characteristic features of my invention are fully disclosed in the following description and the accompanying drawings in illustration thereof.

In the drawings, Figure 1 is a sectional view of a cell cover having my improved vent plug applied thereto; Fig. 2 is a top plan view of the body of the plug illustrated in Fig. 1; and Fig. 3 is a sectional view illustrating a second form of the invention in combination with part of a cell cover to which it is engaged.

As illustrated in Figs. 1 and 2, the cover 1 is provided with the circular central opening 2, and is slightly tapered from the top downwardly. The plug comprises a circular hollow body 3 having the tapered bearing surface 4 adapted to fit in the opening 2, the circular outer rim or upwardly extending flange 5 beneath which is the bearing surface 6 adapted to rest on the cover, the circular inner rim or upwardly extending flange 7 rising to an elevation below the top of the rim 5, the circular channel 8 formed by the rim, the notches 9 and channels 10 forming gas passages in the rim 5 and the notches 11 in the rim 7, the latter forming passages for draining solution from the channel 8 into the body's central aperture 12 and the interior of the cell. A cap or cover 13 is provided with a circular flange 14 which is slightly tapered to fit on the tapered outer surface of the rim 5, the depending circular flange or apron 15 within the flange 14 and adapted to extend into the channel 8 below the top of the rim 7, and the depending circular flange or apron 16 within the flange 15 and adapted to extend into the orifice 12 below the passages 11. The cap 13 is preferably formed separately from the body 3, but the two may be formed in-

tegrally, or burned together to produce an integral construction when formed separately.

In operation, gas escapes freely through the tortuous channel formed by the parts 16 and 7, 15 and 5, and the passages 11, 9, and 10, while solution thrown into the orifice 12 is baffled by the parts 16, 7, 15 and 5, and drains back to the orifice, directly from the surface of the part 16 and indirectly, through the channel 8 and passages 11, from the surfaces of the parts 5, 15 and 7.

It will be understood that the plug can be readily removed to give access to the interior of the cell through the aperture 2.

As illustrated in Fig. 3, the cover 21, having the threaded aperture 22 therein, is combined with the hollow plug body 23 having the threaded ring 24 engaged in the aperture and the bearing surface 26 resting on the cover; the body being provided with the threaded outer rim 25, the inner rim 27, the channel 28, the passages 29 and 30 in the outer rim and the passages 31 in the inner rim connecting the channel 28 with the orifice 32. A cap 33 is fixed on the body, having an outer flange 34 internally threaded to engage the outer rim 25, the depending apron or flange 35 disposed in the channel 28, and the depending inverted cone 35 extending into the orifice 32. Gas can escape freely through the passages 32, 31, 28, 29 and 30, while the escape of solution is baffled by the overlapping parts 27, 35, and 25. Solution which is thrown through the orifice 32 against the cap or cover 33 is drained back from the surfaces of the parts 36 and 35, from the latter into the channel 28, and thence through the passages 31 and orifice 32 into the interior of the cell.

It will be seen that these caps are not only effective for preventing the escape of solution while permitting the escape of gas and the inspection of the interior of the cells, but that they also prevent the introduction of dust, dirt and any other objectionable foreign matter from the exterior to the interior of the cells.

Having described my invention, I claim:

1. A vent plug having upwardly extending flanges forming a channel, a downwardly extending flange disposed in said channel, and an escape passage from said channel

through one of said flanges, in combination with a cell cover having an aperture therein with which said channel communicates.

2. A vent plug having a hollow body, an outer rim, an inner rim, a channel formed by said rims, a notch in said outer rim, a notch in said inner rim, and a cover connected with said outer rim, in combination with a cell cover having an aperture there-
10 through.

3. A vent plug comprising, in combination with a cell cover having an aperture therethrough, a hollow body, a flange thereon having a passage therethrough, a second
15 flange thereon having a passage there-
through communicating with said aperture,

said flanges forming a channel, and a cap fixed to one of said flanges and extending over said channel and apertures.

4. A vent plug comprising a body having an aperture therethrough, and a channel extending around said aperture, in combination with a cap having a flange extending into said channel and a draining device thereon depending into said aperture. 20 25

In witness whereof I have hereunto set my name this third day of June, 1911, in the presence of the subscribing witnesses.

JAMES R. SLOAN.
